[57] **CLAIM**

The ornamental design for a platform for a baby diaper changing station, as shown and described.

DESCRIPTION

FIG. 1 is an upper perspective view of a platform for a baby diaper changing station with a platform in an opened position on a wall and incorporating the new design of the invention, shown in full lines, with the broken lines illustrating the environment of the design;

FIG. 2 is a lower perspective view thereof with the platform of the baby diaper changing station in an opened position; FIG. 3 is a front perspective view thereof with the platform of the baby diaper changing station in closed or stowed position against the wall;

FIG. 4 is a front view of the platform for a baby diaper changing station platform with the platform in the closed position;

FIG. 5 is a front view of the platform for a baby diaper changing station with the platform in the closed position; FIG. 6 is a side view of the platform for a baby diaper changing station with the platform in the opened position with the other side view being a mirror image thereof;

FIG. 7 is a side view of the platform for a baby diaper changing station with the platform in the closed position with the other side view being a mirror image thereof;

FIG. 8 is a top view of the platform for a baby diaper changing station with the platform in the opened position; FIG. 9 is a top view of the platform for a baby diaper changing station with the platform in the closed position;

FIG. 10 is a bottom view of the platform for a baby diaper changing station with the platform in the opened position; and,

FIG. 11 is a bottom view of the platform for a baby diaper changing station with the platform in the closed position.
